UNITED STATES PATENT OFFICE.

BEN A. RAYNOR, OF MUSKOGEE, OKLAHOMA.

RAIL-JOINT.

1,302,971.

Specification of Letters Patent.

Patented May 6, 1919.

Application filed March 8, 1918. Serial No. 221,267.

To all whom it may concern:

Be it known that I, BEN A. RAYNOR, a citizen of the United States, residing at Muskogee, in the county of Muskogee and 5 State of Oklahoma, have invented new and useful Improvements in Rail-Joints, of which the following is a specification.

This invention relates to rail joints and has for its primary object to provide a strong, 10 reliable and efficient means for firmly holding the rails together to prevent creeping, spreading or vertical movement of the rails.

Other objects and advantages will appear as the nature of the invention is better understood, reference being had to the accompanying drawings, in which,

Figure 1 is a side elevation of a rail joint constructed in accordance with this invention.

20 Fig. 2 is a sectional view approximately on the line 2—2 of Fig. 1.

Fig. 3 is a sectional view approximately on the line 3—3 of Fig. 1.

25 Fig. 4 is a perspective view of one of the rail joint members, looking toward the inner face thereof.

Fig. 5 is a transverse sectional view illustrating a modification.

30 Fig. 6 is a perspective view of one of the base members illustrated in Fig. 5.

Fig. 7 is a similar view of one of the angle or flange members.

In the drawings the numerals 10 designate 35 the abutting ends of two rails which are connected in accordance with this invention.

Beneath the rails, and either resting on or 40 arranged between certain of the ties for the rails is my improvement. The improvement, in the preferred embodiment of the invention comprises a chair constructed of two similar sections each including a base 11 on which the rails rest. The base, on the outer edge thereof is integrally formed with an inwardly extending plate or flange 12, the under face of which being arranged at 45 an inclination as indicated by the numeral 13 and this face is adapted to rest on the upper face of the base flange of the rails 10. Passing through the plate or flange 12, the 50 base flanges of the rails and the base 11 of the joint chair members are bolts 14, the same having their threaded ends extending above the straight faces of the flange 12 and the said ends engaged by the nuts 15. Suit-

able means may be provided for locking the 55 nuts on the bolts if desired.

The straight base portion 11 of each of the joint chair sections terminates approximately centrally of the rails 10, and is provided, upon its inner edge with a depending 60 vertically disposed flange 16. The flanges 16, upon the confronting faces thereof are provided with longitudinally extending ribs 17 and depressions 18 between the ribs, and the ribs 17 of one of the flanges are designed 65 to be received in the depressions or grooves 18 of the co-acting flange. Passing through the flanges 16 are bolts 19 which are engaged by nuts 20 and these nuts may be also provided with any suitable means for locking 70 the same on the bolt.

In Figs. 5 to 7 the base members 21 of the joint chair sections 22 are not integrally formed with the over-lying flanges, but in other respects are substantially similar to 75 the construction previously described. The base of each of the sections 22 is provided with a longitudinally extending depressed portion 23 and these alining depressed portions provide a pocket for the base flange 80 of the rails 24. The numeral 25 designates the removable rail engaging plates, the same resting upon the straight upper faces of the base members 21, outward of the pocket 23 and being of a length equaling the length of 85 the remainder of the chair. The members 25 have their under faces, from their inner edges beveled or arranged at an angle as indicated by the numerals 26 and these angular sections contact with the upper faces of 90 the base flanges of the rails. The members 25 are secured on the base of the chair sections through the medium of bolts 27 which pass through suitable openings in the base portions 21 and through the members 25 as 95 well as through suitable openings in the base flange of the rails. The threaded ends of the bolts are projected beyond the outer face of the members 25 and are engaged by nuts 28, any suitable means being provided 100 for locking the nuts, if desired. By reference to the drawings it will be noted that the ribs are substantially V-shaped in cross section and provide substantially V-shaped grooves therebetween. The ribs and grooves 105 are arranged longitudinally over the entire inner surfaces of the depending flanges. The V-shaped construction of the tongues per-

mits of the same being readily inserted in the grooves, and when the nuts are tightened on the bolts a tight frictional engagement is afforded between the co-engaging tongues 5 and grooves.

It is believed, from the foregoing description that the simplicity and advantages of the construction will be apparent without further detailed description.

10 Having thus described the invention what I claim is:

A rail joint comprising a chair constructed of two members each including a base on which the rails rest, the base portion

of each of the members, at the confronting ends thereof, having a depending flange, the confronting faces of the said flanges having their entire surfaces provided with longitudinally arranged substantially V-shaped tongues and substantially V-shaped grooves 20 between the tongues, the said tongues and grooves extending the entire length of the flanges, the tongues on one of the flanges designed to be received in the grooves of the co-acting flange, and transverse binding elements connecting the flanges.

In testimony whereof I affix my signature.

BEN A. RAYNOR
